UNITED STATES PATENT OFFICE.

HENRY F. JUERGENS, OF NEW YORK, N. Y.

DESIGN FOR A BOW-CLASP.

43,245.

Specification for Design.

Patented Nov. 12, 1912.

Application filed September 17, 1912. Serial No. 720,908. Term of patent 3½ years.

To all whom it may concern:

Be it known that I, HENRY F. JUERGENS, a citizen of the United States, and residing in the borough of Manhattan, in the city of New York, county and State of New York, have invented a new, original, and ornamental Design for a Bow-Clasp, of which the following is a specification, reference being had to the accompanying drawing, forming part thereof.

Figure 1 is a front view of a bow clasp showing my new design; Fig. 2 a side view; and, Fig. 3 an end view thereof.

I claim;

The ornamental design for a bow clasp as shown.

HENRY F. JUERGENS.
